UNITED STATES PATENT OFFICE

ALBERT H. WARTCHOW, OF OAKLAND, CALIFORNIA

FOLDING BED

Application filed June 29, 1927. Serial No. 202,286.

This invention relates to new and useful improvements in beds, and particularly to folding beds, of the type which include a base supported on casters, and having the 5 spring bottom frame movably connected thereto and arranged to be swung into vertical position, at times, and into horizontal position at times.

In beds, heretofore, of this type, persons 10 have suffered injury, due to the fact that the spring bottom frames were not properly connected to the bases, and when attempting to swing such frames downwardly, or upwardly, said frames would fall onto the persons.

15 It is the principal object of the present invention to provide a bed of this character wherein the spring bottom frame is so mounted on the base that when swinging the same either upwardly or downwardly, the center 20 of gravity will be also shifted, with the result that said frame will not be liable to fall on the operator.

Another object is to provide a bed of this 25 character which is simple in construction, strong and durable, and which can be easily and safely operated.

Other objects and advantages will be apparent from the following description when taken in connection with the accompanying 30 drawings.

In the drawings:

Figure 1 is a top plan view of a bed made in accordance with the present invention, the bed being shown in lowered, or operative 35 position.

Figure 2 is a side elevation of the same.

Figure 3 is an enlarged vertical longitudinal sectional detail view on the line 3—3 of Figure 1.

40 Figure 4 is a fragmentary vertical sectional view, showing the spring bottom frame in elevated position.

Figure 5 is an enlarged vertical transverse sectional view on the line 5—5 of Figure 1.

45 Referring particularly to the accompanying drawings, 10 represents a base formed from strips of angle metal, and having approximately rectangular outline. The corners of said base, or frame, are connected together by means of the metal plates 11, and

carried by each of these plates is a caster 12, which support the base, and permit movement thereof from place to place. Disposed on the horizontal wings of the end members of the base frame, is a carriage 13, which includes the bars 13' arranged to slide through openings 14, formed in the vertical wing of an end of the rear side member of said base. The rear end of each of the bars 13' is turned upwardly, at right angles, as at 15, and to these upturned ends is secured the head 16, of the bed. The inner end of each of the bars 13' is folded over laterally, as at 17, and rotatably supported within the lower portion of the fold are two rollers 18, which bear on the upper face of the said horizontal wing of the end member of the base frame. On one side of the folded portion of the bar 13', and depending below said wing, is a tab 19, which carries a roller 20, said roller engaging with the lower face of said wing, whereby to maintain the bar in proper sliding engagement with said wing, and effectively preventing tilting movement of said bar, with relation to the wing. Formed on the inner end of the bar, and extending vertically therefrom, is a standard 21, to which is pivotally connected one of the side rails 22, of the bed bottom, or spring frame 23. On each of the side rails 22, outwardly of the 55 pivotal connection with the standard 21, is a collar 24, and pivotally connected at one end to this collar, and at its other end to one of the front corner plates 11, is a link 25. Pivotally connected to the outer end of each of the side rails 22, are the links 26, and pivotally connected to the other ends of said links is a supporting leg 27, which, when the bottom frame is in lowered, or horizontal position, is adapted to stand vertically beyond the transverse spring carrying bar 28, which connects the outer ends of the side rails 22, and when said leg is in such position the weight of the outer end of the bed bottom frame rests on the adjacent link 26, while the other link performs the function of a brace. These links, together with the leg 27, are adapted to be folded back against the side rail of the bed, before the spring frame 60 is swung into vertical position. The other 65 70 75 80 85 90 95 100

ends of the rails 22 are connected by a bar 29, similar to the bar 28, and connected to, and extending between these bars, is the spring bottom of the bed, represented by the numeral 30.

When the bed is in lowered position, the parts are in the position shown in Figures 1, 2, and 3, of the drawings. It will be noted that the carriage 13 has been moved rearwardly on the base frame, so that the head member 16 is in proper spaced relation to the adjacent end of the spring bottom frame. The head end of the bottom frame rests on its pivotal connections with the standards 21, while the foot end of the frame is supported by the legs 27. To fold the bed, the operator grasps the transverse bar 28, and, after having folded the legs 27 against the rails 22, swings the spring bottom frame upwardly, on the pivotal connections thereof with the standards 21. As the frame moves upwardly, the said pivotal connections, together with the links, which are connected with the base, cause the base to move in the direction of the head of the bed, while the bars 13' are drawn outwardly, carrying the head member therewith. This movement causes the shifting of the standards to a position to the front of the rear casters of the base, with the result that the spring bottom frame will properly stand in a vertical position on the base, and any tendency to tilt, forwardly or rearwardly, obviated.

What is claimed is:

- 35 1. A folding bed including a base, a carriage, means by which the carriage is horizontally slidably on the base, said carriage having uprights, a bed bottom pivotally connected at one end to the uprights for movement from vertical to horizontal position, and links connected with the bed bottom and said base whereby to cause the carriage to slide rearwardly on the base when the bed bottom is moved from vertical to horizontal position.
- 40 2. A folding bed including a base, a head-board member including bars slidably supported on the sides of the base, said bars having uprights on their inner ends, a bed bottom pivotally connected at its inner end with the upper ends of the uprights and adapted to stand vertically, at times, and horizontally, at times, and links connected with the bed bottom forwardly of the uprights and with the forward end of the base, said links serving to produce relative slidable movement of the base and head-board member bars as the bed bottom is swung from one position to another.
- 45 3. In testimony whereof, I affix my signature.
ALBERT H. WARTCHOW.
